Primary Examiner — Brett Miller*Assistant Examiner* — Jessica M Gebhart(74) *Attorney, Agent, or Firm* — Coleman and MacDonald Law Office(57) **CLAIM**

The ornamental design for a roof caddy, as shown and described.

DESCRIPTION

FIG. 1 is a front side perspective view of a roof caddy showing my new design;

FIG. 2 is a rear side perspective view of the roof guard of FIG. 1;

FIG. 3 is a front view of the roof caddy of FIG. 1;

FIG. 4 is a rear view of the roof caddy of FIG. 1;

FIG. 5 is a left side view of the roof caddy of FIG. 1;

FIG. 6 is a right side view of the roof caddy of FIG. 1;

FIG. 7 is a top view of the roof caddy of FIG. 1; and,

FIG. 8 is a bottom view of the roof caddy of FIG. 1.

The broken lines are illustrative of environmental structure only and form no part of the claimed design.

1 Claim, 7 Drawing Sheets(56)
